UNITED STATES PATENT OFFICE

2,351,059

FILLING MACHINE

William McK. Martin, Maywood, Ill., assignor to
American Can Company, New York, N. Y., a
corporation of New Jersey

Application April 15, 1941, Serial No. 388,683

3 Claims. (Cl. 226—69)

The present invention relates to liquid filling machines and has particular reference to breaking up foam formed on the surface of the liquid in the machine by bursting the foam bubbles with a spray of the liquid being filled.

In the filling of containers such as cans and bottles with certain liquids, such as for example, milk, considerable foaming of the liquid sometimes takes place. The foam collects on the surface of the liquid in the filling machine. In some filling machines, vent tube openings or ports associated with liquid measuring chambers or filling valves are often necessarily located immediately above the surface of the liquid. With such machines the accumulation of foam around these openings or ports often results in improper operation of the filling devices with occasional slack filling of the containers.

The instant invention contemplates overcoming these difficulties by providing means for bursting the foam bubbles on the surface of the liquid in the immediate vicinity of the openings or ports by directing against the foam a horizontal spray or jet of the liquid being filled.

An object therefore of the invention is the provision in a machine for filling liquids into containers, of devices which operate to draw up a stream of the liquid in the tank and to project it outwardly and horizontally by centrifugal action in a cutting jet or spray which bursts the foam bubbles in the region of the filling elements so that the foam will be prevented from passing out with the liquid during the fill and thereby avoid slack filling of the container.

Numerous other objects and advantages of the invention will be apparent as it is better understood from the following description, which, taken in connection with the accompanying drawing, discloses a preferred embodiment thereof.

Referring to the drawing:

Figure 1 is a vertical sectional view of a portion of a liquid filling machine embodying the instant invention, with parts broken away;

Fig. 2 is a plan or horizontal section taken substantially along the broken line 2—2 in Fig. 1, with parts broken away;

Fig. 3 is an enlarged elevational detail, with parts broken away;

Fig. 4 is a sectional view taken substantially along the line 4—4 in Fig. 3, with parts broken away; and

Fig. 5 is a fragmentary view of the same detail as that of Fig. 3 but showing the opposite side thereof.

As a preferred embodiment of the invention the drawing illustrates principal parts of a milk filling machine of the character disclosed in United States Patent 2,222,617, issued November 26, 1940, to J. M. Hothersall et al., on Filling machine. Such a machine fills accurately measured charges of milk into fibre containers A (Fig. 1).

The milk, designated by the letter B, to be filled into the containers A is preferably retained in a rotatable reservoir or tank 11 which is formed adjacent its outer edge with a plurality of spaced depending hollow filling heads 12. The bottom of each head is fitted with a cap 13 having a depending filling nozzle 14 with a vertically movable valve 15. The nozzle is adapted to be inserted into the container A for filling.

Each filling head 12 contains a vertically movable hollow bottle-shaped measuring element 21 having an open bottom and having a reduced diameter tubular neck or levelling tube 22 which extends up through the milk in the tank 11 and projects above the surface of the milk. The levelling tube is formed with a pair of oppositely disposed measuring ports 23 which are located just above the surface of the milk in the tank.

When the machine is in operation and the valve 15 in the nozzle 14 is closed, the measuring element 21 is lifted vertically sufficiently to permit milk to flow from the tank into the measuring element through its open bottom. The milk accordingly fills the measuring element to the level of the milk in the tank. This level in the measuring element is just below the levelling ports 23 in the levelling tube 22.

When filled, the measuring element moves down against the filling head cap 13 and its bottom is thereby closed off from the tank. This segregates the milk in the measuring element from that in the tank. The downward movement of the measuring element also forces some of the segregated milk upwardly into the levelling tube 22 so that some of it will overflow back into the tank through the levelling ports 23. When the overflowing has ceased there is left remaining in the measuring element a predetermined and accurately measured charge of milk. The valve 15 is then opened and the measured charge of milk discharges into the waiting container A by way of the nozzle 14.

Agitation of the milk in the tank usually forms foam on its surface level. In order to prevent this foam from entering the levelling ports 23 and thus being drawn down into the measuring

chamber 21 when the measured charge of milk is emptied into a container A, the foam in the region of the filling elements is broken up and destroyed.

Breaking up of the foam is preferably brought about by a centrifugal pump device generally indicated by the numeral 25 in Fig. 1. This pump device includes a flat disc 26 which is located in the tank 11 at the filling station of the machine and is disposed parallel with and closely adjacent to but not touching the surface level of the milk in the tank.

The disc 26 is formed with a depending conical sleeve 27 (see Figs. 3, 4 and 5) which is located at the center of the disc and which extends down into the milk in the tank 11. The sleeve fits over a conical hub 28 formed on the lower end of a vertical rotor shaft 29 of an electric motor 31 mounted on a stationary bracket 32 bolted to the main frame of the machine. A shoulder flange 35 on the hub 28 forms a seat for the disc 26 and a bayonet connection comprising a pin 36 in the hub and a bayonet slot 37 in the sleeve, holds the disc securely on the hub. This bayonet connection provides a quick and easy means of taking the members apart for cleaning.

The open bottom end of the conical sleeve 27 as at 41, communicates with an aligning groove or port 42 which is cut in a side of the hub 28. The bottom end of this groove terminates concentrically with the axis of the hub. The groove 42 extends upwardly along the hub and terminates adjacent the bottom of the disc 26. This upper terminal end of the groove communicates with an aperture 44 formed in the sleeve 27 at the bottom of the disc. Aperture 44 leads to a U-shaped guide or channel member 45 (Figs. 2 and 5) one leg of which lies flat against and is secured to the bottom of the disc in a radial position. The outer end of the channel member terminates adjacent the periphery of the disc.

The electric motor 31 while the machine is in operation, rapidly rotates its rotor shaft 29 and the disc 26 secured thereto in the direction of the arrow shown in Fig. 2. The rapidly rotating shaft and disc revolves the sleeve 27 and hub 28 in the milk. Since the upper end of the groove 42 is eccentrically located relative to the axis of the hub while the lower end of the groove is concentric with the axis, a centrifugal pumping action is set up which draws the milk up into the groove and discharges it from the hole 44 in the sleeve. The discharged milk flows along the channel member 45 and is thrown off the outer end of the channel member, by centrifugal force of the rotating disc. This discharge is in the nature of a rapidly flowing horizontal stream or jet of small drops of the liquid, as indicated by the numeral 51 in Fig. 2.

As the disc 26 rotates, the jet 51 of milk droplets impinges against and cuts into the foam immediately above the surface level of the milk in the tank with sufficient force to burst the foam bubbles and thereby destroy the foam.

Hence as the tank 11 rotates and brings each filling head 12 in succession into position at the filling station to empty its measured charge of milk into its container A, the rotating pump device 25 becomes effective as to such filling head. The pumping device 25 thus destroys the foam in the region of the levelling ports 23 in the levelling tubes of the measuring elements 21 of the advancing head. This prevents the foam from being drawn down into the measuring ele-

ments. Accurate measuring functions therefore result in the filling cycles of the filling heads.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for filling foam producing liquids into containers, the combination of a tank for retaining a quantity of the liquid, a filling unit for discharging liquid from said tank into a container, a vertically disposed rotatable shaft located in said tank, means for rotating said shaft, a conical hub on the lower end of said shaft, said hub extending down into the liquid and having a vertically inclined passageway the lower end of which is concentric with the hub axis and the upper end of which terminates at the outer surface of the hub, a disc removably secured to said hub with its bottom surface parallel with and closely adjacent the surface of the liquid in the tank, a conical sleeve on said disc and fitting over said hub, said sleeve at its bottom communicating with the lower end of said passageway and having an aperture adjacent the disc communicating with the upper end of said passageway for drawing liquid upwardly through said hub, and a channel member secured to the bottom of said disc extending from said hole to the outer edge of the disc for throwing the drawn up liquid centrifugally as a horizontal spray immediately above the surface of the liquid in the tank, whereby to prevent development of foam within a predetermined region on the surface of the liquid.
2. In a machine for filling foam producing liquids into containers, the combination of a tank for retaining a quantity of the liquid, a filling unit mounted on said tank for receiving and discharging liquid from said tank into a container, a vertically disposed rotatable shaft located in said tank, a rotatable centrifugal pump mounted on said shaft and extending beneath the level of the liquid in said tank, said pump having a horizontal surface portion spaced above said liquid level, said pump also having an upwardly and outwardly inclined port terminating at its upper end directly beneath said horizontal surface portion, the lower end of said port terminating beneath said liquid level, means for rotating said shaft and pump to draw the liquid in the tank upwardly through said port to discharge such liquid directly beneath the pump horizontal surface portion and throw the liquid outwardly adjacent said filling unit and over the surface of the liquid in the tank, whereby to destroy foam on the liquid to prevent such foam from reaching said filling unit and thence passing into the container during the filling operation.
3. In a machine for filling foam producing liquids into containers, the combination of a rotatable tank for retaining a quantity of the liquid, a plurality of spaced filling heads mounted on said tank adjacent its periphery and movable with the tank through a container filling station, a measuring element disposed in each of said filling heads, a leveling tube on each of said measuring elements, a said leveling tube having leveling ports disposed immediately above the surface level of the liquid in the tank for admitting tank liquid to its associated measuring element, a ver-

tically disposed rotatable shaft located in said tank, a rotatable centrifugal pump mounted on said shaft and extending beneath the level of the liquid in said tank, said pump having a horizontal surface portion spaced above said liquid level, said pump also having an upwardly and outwardly inclined port terminating at its upper end directly beneath said horizontal surface portion, the lower end of said port terminating beneath said liquid level, means for rotating said shaft 10

and pump to draw the liquid in the tank upwardly through said port to discharge such liquid directly beneath the pump horizontal surface portion and throw the liquid outwardly adjacent said filling heads and over the surface of the liquid in the tank, whereby to destroy foam on the liquid to prevent such foam from reaching said filling heads and thence passing into the container during the filling operation.

WILLIAM McK. MARTIN.
